(57) **CLAIM**

The ornamental design for a carrier for samples or reagents, as shown and described.

DESCRIPTION

FIG. 1 is a top plan view of a carrier for samples or reagents, according to my invention;

FIG. 2 is a side elevational view thereof, the opposite side being identical;

FIG. 3 is a plan view from beneath,

FIG. 4 is an end elevational view, the opposite end being identical,

FIG. 5 is a cross-sectional view taken along lines V—V of FIG. 1; and,

FIG. 6 is a cross-sectional view taken along lines VI—VI of FIG. 1.
